BACK-PRESSURE CHECK VALVE

Jarrett L. Cameron, Orangefield, and Frank J. Malloy, Orange, Tex., assignors to Levingston Shipbuilding Company, Orange, Tex., a corporation of Texas

Application February 8, 1945, Serial No. 576,780

12 Claims. (Cl. 137—152)

1

This invention relates to back pressure check valves of a type intended more particularly for use in connection with well drill stems and the like.

The chief aim of our invention is to provide a back pressure check valve for well drill stems, which is simple in construction and inexpensive to produce; and which can be relied upon to automatically close in the event of development of back pressures in the wells and so obviate what are known as drill stem blow-outs, i. e., forcible discharge of fluids either in liquid or gaseous form through the stems.

In connection with a back pressure check valve having the above attributes, it is a further aim of our invention to incorporate detent means which will temporarily hold the closure element of the valve in open position so that string tools such as are ordinarily employed in drilling may be lowered through the stem without hindrance and the stem at the same time allowed to fill with mud, but which will yield to downward displacement upon injection of drill fluids into the stem as the drilling operation is commenced to release the closure element of the valve for subsequent automatic operation in emergencies such as above referred to.

Other objects and attendant advantages will appear from the following detailed description of the attached drawings, wherein

Fig. 1 is an axial sectional view of a back pressure check valve for well drill stems conveniently embodying the present invention with the parts positioned in readiness for connection to the drill stem.

Fig. 2 is a fragmentary view corresponding to Fig. 1 showing how the valve parts are initially positioned within the valve housing.

Fig. 3 is a view in turn like Fig. 2 showing the valve in closed position.

Fig. 4 is a cross section of the valve taken as indicated by the angled arrows IV—IV in Fig. 1.

Fig. 5 is another cross sectional view taken as indicated by the angled arrows V—V in Fig. 1.

Fig. 6 is a fragmentary axial section taken as indicated by the angled arrows VI—VI in Fig. 3. Fig. 7 is a perspective view of the closure ele-

our improved check valve comprises shouldered subs 10 and 11 which are joined by a threaded pipe sleeve coupling 12 with resultant provision of a diametrically enlarged valve cavity or chamber 13, and which are respectively formed with internally and externally threaded end portions 15 and 16 for connection of contiguous parts or sections (not shown) of a well drill stem. Located within the valve chamber 13 is a pivotally 5 hung closure flap 17 which is curved in cross section, and which, when in open position is substantially concentric with the valve axis and lies substantially snug against the inner face of a coupling sleeve 12 as shown in Figs. 1 and 4, and 10 15 20 25 10 hung closure flap 17 which, when in closed position as shown in Fig. 6, bears snugly against the correspondingly rounded seat 18 at the bottom end of the sub 10 within the top of the chamber 13. The pivot connection for the closure flap 17 comprises a small plate 19 (Fig. 8) which is fitted into the side of the upper sub 10 and secured by a pair of screws 20 (Fig. 1). At its lower end, the plate 19 is formed with a hook 21 to outwardly engage within a rectangular aperture 22 in the closure flap adjacent 25 the edge thereof.

The actuating member of the valve is in the form of a tubular piston 23 which has a flared head 24 at the top surrounded by a band 25 of rubber or the like for fluid-tight fitment circumferentially within the coupling sleeve 12. The diameter of the body portion of the piston 23 is somewhat less than that of the enlarged bore portion 26 at the upper end of the sub 11 with resultant provision of a clearance 27 all around it when said piston is in the lowered position of Fig. 1. Medially of its height, the piston 23 has a circumferentially notched guiding flange 28 that slidably engages the interior of the coupling sleeve 12, said flange being adapted to rest on the annular shoulder formed by the top end of the sub 11 within the valve chamber. Slidably engaged within the piston 23 is a tubular detent element 30 with a stop flange 31 at its upper end, the bore of said element being equal in diameter to that of the main bores 32 and 33 of the subs 10 and 11 and internally beveled at the top at an angle corresponding to the internal flare of the head 24 of said piston. As shown, the sub 11 is likewise beveled internally of the top of its bore as at 35. The detent element 30 is moreover provided with circumferential recesses 36 and 37 whereof the upper one is occupied by a packing band 38 of rubber or the like and the lower one by a split spring band 39, said band 39 being held in place by a nut collar 40 threadedly engaged on

the protruding bottom end of the element 30 and secured against accidental displacement by a set screw 41. For reasons also hereinafter explained the piston 23 is provided immediately below its flared head 24, with downwardly and outwardly inclined apertures 42, and the spring band 39 with circumferentially arranged perforations 43 and 44 respectively adjacent its upper and lower edges.

In assembling the valve, the spring band 39 is compressed and the detent element 30 inserted into the tubular piston 23 as shown in Fig. 2 with its upper end projecting, whereupon the nut collar 40 is applied and secured by the set screw 41. With this accomplished, the piston 23 is inserted into the coupling sleeve 12 and the bottom sub 11 finally screwed into place, the movable parts being then positioned as in Fig. 2 with the edge of the flared head 24 of said piston engaging behind the closure flap 17 which is chamfered as at 17a to permit this. The assembled valve, made ready as just explained, is then connected to the drill stem adjacent the lower end of the latter preferably just above the drill collar.

With the closure flap 17 held open as in Fig. 2 it will be seen that the main bores of the subs 10 and 11 are entirely unobstructed so that string tools such as drills, swabs, gages or stirrers ordinarily used in normal operations inside the drill stem may be readily introduced through said stem from above without hindrance. Temporary locking of the valve in open position is advantageous incident to the drilling since it allows the weight of the mud to remain in the hole, and at the same time eliminates any air which might accumulate and which would have to be otherwise released before drilling or circulation of mud is started. The parts will remain in the positions in which they are shown in Fig. 2 until the mud pumps are started and the drilling is commenced. Upon passage of the drilling fluid under pressure downward through the valve, the detent element 30 will yield to displacement and descend within the piston 23 until its stop flange rests on top of the sub 11 as shown in Fig. 1, with attendant freeing of the spring band 39 which consequently will expand and coact with said stop flange to prevent subsequent rise of said element within said piston. Thereafter throughout the drilling operation the movable parts of the valve will remain in the position of Fig. 1. However, if back pressure should for any reason develop in stem from within the well, the piston 23 and the detent element 30 will be bodily raised by direct action of the pressure against the bottom of the nut collar 40 and the bottom of the head 24 with the result that upon withdrawal of the tool string to a level slightly above the seat 18, the closure flap 17 will be swung inward by action of the flare on said member and will itself be subjected to the force of the pressure from below and thereby be moved to the fully closed position in which it is shown in Fig. 3. The drain apertures 42 in the member 23 allow circulation in the event that fine sand particles should by-pass the packing ring 25 and so prevent clogging; while the perforations 43 and 44 in the split ring permit the fluid used in the drilling to augment the spring effect of the ring and thereby assist in counteracting the external pressure which would tend to collapse said ring. In this way, we insure against rising of the detent tube to its original elevated holding position after it has once been depressed.

Although our improved back pressure check

valve can be interposed at any desired point in the drill stem, we preferably place it, as previously stated, near the bottom of the stem just behind the drill collar (not shown) of the bit. In practice its external dimensions are made equal to that of the tool joint and its internal dimensions slightly larger than those of the drill stem proper.

Having thus described our invention, we claim:

1. A check valve for a connection axially of a hollow well drill stem or the like including a tubular valve casing; a closure element adapted to cooperate with a valve seat within the casing; detent means for initially holding the closure element away from its seat but capable of responding to a predetermined velocity of fluid through the valve casing from above to release the closure element; and actuating means capable of responding subsequently to a predetermined velocity of fluid in the opposite direction to move the closure element into engagement with its seat.

2. A check valve according to claim 1, in which there is a diametrically-enlarged chamber medially of the valve casing; in which the closure element is in the form of a pivotally-suspended flap curved and normally positioned at one side of the chamber substantially in concentric relation to the chamber wall; and in which the seat against which said flap closes is correspondingly curved.

3. A check valve for connection axially of a hollow well drill stem or the like including a tubular valve casing providing a diametrically enlarged chamber; a pivotally-suspended closure flap adapted to cooperate with a valve seat at the top of the chamber and normally in open position; and a tubular actuating piston adjacent the bottom of the chamber having a projection at the top reaching behind the valve flap, said piston being responsive to upward displacement by a predetermined velocity of fluid in the valve casing from below to move the closure flap into engagement with its seat.

4. A back pressure check valve according to claim 3, in which the piston has a head flange surrounded by a band of resilient material for fluid-tight fitment within the chamber.

5. A back pressure check valve according to claim 3, in which the valve casing comprises a pair of axially aligned subs in spaced relation and respectively provided with coupling means, and a tubular coupling sleeve connecting the contiguous ends of the two subs.

6. A back pressure check valve according to claim 3, further including a detent element in the form of a tube within the piston, and associated means for initially holding the tube projected above the piston in the path of the closure flap to prevent closing of the latter, said detent element being displaceable downwardly by a predetermined velocity of fluid in the valve casing from above so as to release said flap in readiness for actuation by the piston.

7. A back pressure check valve according to claim 3, further including a detent element in the form of a tube within the piston, and associated means for initially holding the tube projected above the piston in the path of the closure flap to prevent closing of the latter, said detent element being displaceable downwardly by a predetermined velocity of fluid in the valve casing from above so as to release said closure flap in readiness for actuation by the piston; and automatically operative means for locking the detent element against movement, relative to the piston after it has once been depressed.

8. A check valve for connection axially of a hollow well drill stem or the like including a tubular valve casing providing a diametrically-enlarged chamber; a closure flap pivotally suspended in the chamber at one side and adapted to cooperate with a valve seat at the top of the chamber; a tubular actuating piston adjacent the bottom of the chamber having a head flange which reaches behind the closure flap, said piston being responsive to upward displacement by a predetermined velocity of fluid in the valve casing from below to move the flap into engagement with its seat; and a tubular detent slidably engaged in the piston for initially holding the flap in open position, and responsive to downward displacement by a predetermined velocity of fluid in the valve casing from above and having a stop shoulder at the top; and a split spring band lodged in a circumferential recess at the lower end of the detent for frictionally engaging the bore of the piston to hold the tube up in the path of the flap and adapted, upon depression of the tube, to expand and coat with the aforesaid stop shoulder in locking the tube to the piston.

9. A back pressure check valve according to claim 8, in which the head flange of the piston is surrounded by a band of resilient material for fluid-tight fitment within the valve chamber; and in which the detent has a jacket of similar material above the split band for fluid-tight fitment within the piston when in its lowered position.

10. A back pressure check valve according to claim 8, in which the head flange of the piston is surrounded by a band of resilient material for fluid-tight fitment within the valve chamber; in

which said piston is provided immediately below its head flange with a circumferential series of downwardly and outwardly inclined apertures; and in which the detent has a jacket of resilient material above the split spring band for fluid-tight fitment within the piston when in its lowered position.

11. A back pressure check valve according to claim 8, in which the split spring band is provided with a circumferential series of holes which permit entry of fluid to its interior after it has been expanded.

12. A back pressure check valve according to claim 8, in which the head flange of the piston is surrounded by a band of resilient material for fluid-tight fitment within the valve chamber; in which said piston is provided immediately below its head flange with a circumferential series of downwardly and outwardly inclined apertures; in which the detent has a jacket of resilient material above the split spring band for fluid-tight fitment within the piston when in its lowered position; and in which the split spring band is provided with a circumferential series of holes for passage of fluid to its interior after it has been expanded.
